UNITED STATES PATENT OFFICE.

HAVEN C. PERHAM AND ALFRED CLARKE, OF LOWELL, MASSACHUSETTS.

MACHINE FOR OPENING, CLEANING, AND CONDENSING TEXTILE FIBERS.

SPECIFICATION forming part of Letters Patent No. 295,938, dated April 1, 1884.

Application filed June 18, 1883. (No model.)

To all whom it may concern:

Be it known that we, HAVEN C. PERHAM and ALFRED CLARKE, citizens of the United States, residing at Lowell, in the county of Middlesex 5 and Commonwealth of Massachusetts, have invented certain new and useful Improvements in Machines for Opening, Cleaning, and Condensing Textile Fibers, of which the following is a specification.

10 Our invention relates to the wire cages used in machines of the above class for collecting the fibers to form laps, and to means for exhausting air from the same, through the ends thereof, in such a manner as to avoid inequality of draft and unevenness of the laps.

15 In the accompanying drawings, Figure 1 is a vertical central cross-section of the fan-case and fan-shaft bearing, showing also the fan-shaft, its pulley, and the fan in elevation; Fig. 2, a side view of the fan-case and part of the frame of the machine to which it is applied; Fig. 3, a vertical cross-section of a lapper just in front of the cages, showing the cages, the exhaust-pipes, the fan, fan-shaft, and pulley; 20 Fig. 4, a side elevation of a lapper with forward exhaust-pipes, the fan-case being in section.

25 A is the frame of the lapper, standing upon the floor X; B B', the apron-rolls; C, the feed-apron, the apron and one of the apron-rolls, B, being shown by dotted lines; D, the apron side; E E' E'', feed-rolls; F, the beater, shown by dotted lines; F', the beater-shaft; F'', the driving-pulley on the beater-shaft. F''' is the driving-belt. G is the beater-grate. H H' are upper and lower wire collecting-cages; I I', drawing-rolls; J J' J'', calender-rolls; K K', lap-rolls, all of these being of any usual construction and operation, except the modifications hereinafter stated of the cages and their exhausting mechanism. The top of the machine is provided with a cover, L, between the feed-rolls and the calender-rolls, the parts L' 30 L'' over the beater and the cages, respectively, 35 being hinged covers, as usual. There is commonly placed below and a little in front of the wire cages a long fan, which reaches nearly across the machine, and is connected with air-exhaust pipes, which, when the fan is operated, 40 take the air from the ends of the cages, and thereby suck the fibrous material on which the machine is operating onto the front side

of the revolving cages to form a lap, and also drawing more or less dust into the cages through their covering, and out of the ends of the cages 55 through air-pipes to the fan, and through the floor into a proper receptacle or out-of-doors. Such fans as now used are cumbersome, and, owing to their position, cannot readily be examined or repaired while in the machine, and 60 do not always draw the air equally from each end of the same cage, so that the fibers are deposited faster at one end of the cage than at the other, and the resulting lap is thicker at one edge than at the other. To remedy these 65 defects we use two small rotary fans, which, with their cases, are placed one on each side of the machine, and wholly outside of the usual frame thereof. Each fan consists of a hub, m, provided with arms m', to which are secured 70 vanes m'', in the usual manner, by bolts or screws m''. The hub is placed on the fan-shaft M, and secured thereto in any usual manner, as by set-screws m''. The fan-shaft M turns in bearings secured to the side of the case by 75 bolts and nuts P. The bearing shown in Figs. 1 and 2 is formed, for convenience, in three parts, o o' o'', the parts o o' together being in the form of a horizontally divided flanged journal-box, the flanges of the box being bolted 80 to the fan-case, as above described, and the lower half, o', of the box being provided with the bracket o'', which reaches under the driving-pulley M' of the fan and supports the outer end of the fan-shaft. The third part, o'', of the 85 bearing covers the outer end of the fan-shaft, and is secured by screws to the top of the bracket o''. The fan-case is formed by the frame A of the machine, and by a flange, n, cast on said frame, and by a plate, n', held 90 against the flange n by screws S, passing through ears n'', cast on the plate n', and entering the frame A outside of said flange n. By loosening these screws S the fan, with the plate n', may be removed from the machine for examination or repairs. The fan may be driven by a belt, R, connecting the pulley M' with a pulley, F', secured to the beater-shaft. On each side of the machine there is an opening, t, in the frame A, at the center of the fan, into a horizontal trunk or pipe, T, which opens at t' through the frame A into the vertical side pipe, T', and the frame is provided with openings t'' t' at the ends of the cages, respectively,

which openings t^2 t^3 lead into said side pipe, T', so that when the machine is operated air will be drawn from the ends of the cages, causing the fibers operated on by the beater to be drawn from the beater and to adhere to the surface of the cages, and drawing the dust from the fibers into the cages and through the exhaust-pipes T T' into the fan-case, from which they are expelled by the operation of the fan through the opening X' in the floor X into any suitable receiver. The side pipes, T', are removable, being held to the frame by the screws V, which allow of their being removed and cleaned.

15 It will be seen that by varying the speed of the fans relatively to each other the amount of air taken from the opposite ends of the cages may be varied, and that when the machine is first set up the relative speed of the 20 fans may be so adjusted as to produce a lap of uniform thickness from edge to edge, the variation of speed being accomplished by varying the sizes of the driving-pulleys, respectively. These results can be accomplished to 25 considerable extent without alteration of the cages; but we prefer to divide each cage H H' by a circular partition, h h', of sheet metal, placed at right angles to the shafts of said cages, which partitions will require all the air 30 exhausted by one fan to be taken from its end of the cages.

The invention above described is applicable not only to lappers, but also to shoddy-pickers, burr-pickers, and cotton-condensers.

35 We claim as our invention—

1. The combination of one or more lap-collecting cages, and independent means at each

end of such cage or cages for exhausting air from the ends thereof, as and for the purpose specified.

2. The combination of one or more lap-collecting cages, and separate exhaust-pipes—one at each end of said cages—and separate air-exhausting means for each of said pipes, as and for the purpose specified.

3. The combination of one or more lap-collecting cages, and separate exhaust-pipes—one at each end of said cages—and separate exhaust-fans for each of said pipes, as and for the purpose specified.

4. The combination of one or more lap-collecting cages, each provided with a central vertical partition, and independent means at each end of such cage or cages for exhausting air from the ends thereof, as and for the purpose specified.

5. The combination of one or more lap-collecting cages, each provided with a vertical central partition, separate exhaust-pipes—one at each end of said cages—and separate air-exhausting means for each of said pipes, as and for the purpose specified.

6. The combination of one or more lap-collecting cages, each provided with a central vertical partition, and separate exhaust-pipes—one at each end of said cages—and separate exhaust-fans for each of said pipes, as and for the purpose specified.

HAVEN C. PERHAM.
ALFRED CLARKE.
